11 Claims

This invention relates to electronic inspection of printed sheets, such as sheets having carton blanks printed thereon.

In my prior U.S. Patent 3,035,380, "Method for Inspecting Cartons," I disclose a method of electronically inspecting cartons in accordance with which spaced code marks or lines are positioned on the glue lap and on the end flap or tuck of a carton. These code marks are inspected by a photoelectric inspection device which sends a pulse to an electronic counter for each reflecting space between adjacent code lines to cause a count to be registered on the counting device corresponding to the total number of reflecting spaces of the particular code being inspected, and if this count corresponds to the count for which the counting device has been preset, then the carton passes inspection, whereas if the count is different from that which the counter has been preset, then the carton is rejected. The code marks on the glue lap of the carton can be conveniently utilized by the carton manufacturer in the inspection of the carton blanks to determine that all blanks of a particular lot bear identical code marks and corresponding identical printed matter describing the item of material or article to be contained within the carton. This first zone or glue lap inspection takes place at the folding box gluer. The prevailing practice is to fix the glue lap to the under side of the opposite end panel of the carton, whereby the code marks on the glue flap are concealed after the carton has left the carton manufacturer. Instead of having the code lines on the glue lap for zone 1 inspection as shown by my prior U.S. Patent 3,035,380, an equivalent result may be obtained by printing lines elsewhere on the box on a path which parallels the glue lap. The code marks on the end flap or tuck are utilized by the packer in the inspection of the cartons prior to placing material therein, and constitutes a second zone inspection.

It is an object of the present invention to provide a method of electronically inspecting printed sheets having folding cartons printed thereon, to permit making of an initial inspection of the sheet before it has been cut into the individual boxes, which inspection may be followed by one or more inspections such as the first and second zone inspections shown in my prior U.S. Patent 3,035,380, to give a greater degree of security by having a plurality of inspections.

It is another object of the invention to provide a method of electronically inspecting printed sheets before they are cut into boxes whereby stoppages which would normally occur on subsequent inspections may be detected while the boxes are still in sheet form so that the defective sheet may be removed before being cut into boxes, and thereby eliminating possible multiple stoppages.

It is a further object of the invention to provide a method of electronically inspecting printed sheets which provides a greatly increased scope of inspection as compared to prior inspection methods, and which is suitable for inspecting printed sheets having various types of printed material thereon, such as cartons, labels, ad-

2

vertising materials, etc., which are subsequently cut from the printed sheet.

In achievement of these objectives, there is provided in accordance with this invention a method of inspecting sheets on which cartons are printed for the purpose of detecting errors before the sheets are cut into the individual cartons, although the method is not necessarily restricted for use with sheets having cartons printed thereon, but is also applicable to sheets having other printed matter thereon, such as labels, advertising displays and the like. The sheets are coded with code lines which indicate the printing press pass or color, and with additional code lines which indicate the "change"—that is, which designate the particular one of a plurality of successive sheets having different printed material thereon being run through the press on a given pass. In accordance with an important feature of the method, there is provided in the coding area on the sheet following the code lines a solid printed area of sufficient density and length to actuate the time trigger associated with the counter, whereby to reset the counter for a subsequent sheet whether or not a count corresponding to the preset count has been made, and additionally to actuate an alarm relay if a count different from the preset count has been made. In accordance with a modified embodiment, the reset circuit is controlled by a mechanically operated switch controlled by the press mechanism which is operated in timed relation to the movement of the sheets along the feed board to the press cylinder.

Further objects and advantages of the invention will become apparent from the following description taken in conjunction with the accompanying drawings, in which:

FIG. 1 is a schematic view of an apparatus which may be used in practicing the present invention;

FIG. 2 is a view of a sheet having printed cartons thereon and including at one area thereof the coding arrangement of the present invention applied to a sheet prepared for stream feeding into the press;

FIG. 3 is a view illustrating how the coding arrangement may be used to designate the various printing passes through the press made by the sheet, and also to designate the various "changes" made on the respective passes; and

FIG. 4 is a diagrammatic sketch showing the use of a mechanical reset device instead of the electronic reset used in the embodiment of FIG. 3.

Referring to the drawings, and more particularly to FIG. 1, there is shown an electronic sheet inspecting apparatus comprising means for providing an inspection zone, such as the feedboard on the cutting and creasing press, for moving sheets S having code marks thereon through the inspection zone. The sheets S shown in FIG. 1 are being stream fed past the inspection point P, with successive sheets having their ends in overlapped relation to each other. However, the sheets could also be "sheet fed" without being in overlapped relation to each other.

A photoelectric device including light sensitive means such as phototube 11 is focused on a point P through which the sheets are to be passed by the conveyor. A source of light is provided such as a lamp 12, having a filament the reflected image of which preferably falls within the length and width of a code line for directing the narrow light beam B onto the point P, whereby the light is reflected by the spaces between code lines as a beam R onto the light sensitive means of the phototube 11. An electronic counter 14 is electrically connected to the photoelectric device 11 through a thermionic tube 15 which is adapted to transmit impulses to the counter 14 in response to signals produced by phototube 11.

There is shown in FIG. 2 a printed sheet S having a number of carton blanks or forms printed thereon. In the particular embodiment illustrated in FIG. 2, sheet S

has three different types of carton forms printed thereon, namely, the carton forms indicated at A, B and C, respectively. The individual cartons A, B, C, are provided with code lines such as those indicated at 19, 21, 23 for use in subsequent inspection of the individual cartons in accordance with the teachings of my prior United States Patent No. 3,035,380.

The sheet S is assumed to be printed in two colors, such as blue and yellow, for example, on two separate passes. The counter 14 is so constructed and arranged that it can be preset for a predetermined count corresponding to the coding of the particular sheets which are to be inspected. As the sheets pass through the inspection point, the coding is scanned and signals are produced by the phototube and transmitted to the counter.

In order for the counter to be reset for the next sheet, it is necessary that there be an uncocking of the time trigger of the counter by a sufficient interval of unreflecting or dark space. With individually fed sheets, reset occurs when the sheet leaves the inspection point P and the resulting lack of light reflection permits the "trigger" to uncock. With stream feeding, where sheets overlap on the feedboard, it is necessary to print an unreflecting space following the code lines, which space is of sufficient length to permit the trigger to uncock and to actuate the reset. If an over or under count is registered, a relay is actuated to stop the press, permitting removal of the defective sheet. If the proper count has been registered, only counter preset takes place and the inspection continues on to the next sheet.

Referring now to FIG. 2, it will be noted that adjacent the right-hand edge of the sheet S of FIG. 2 there are shown a plurality of code lines or marks generally indicated at 16, followed by a solid printed area 18' of sufficient density and length to actuate a time trigger associated with counter 14. The solid printed area 18' provides the unreflecting or dark space on the sheet S necessary to provide uncocking of the time trigger of the counter on this stream fed sheet, as previously explained. The length of the printed area 18' is properly related to the known rate of feed of the sheets through the inspection zone so as to require the proper time interval for the passage of the printed area 18' through the inspection zone to provide or cause the uncocking of the time trigger of the counter, as previously explained.

The code marks generally indicated at 16 are specifically identified as Y₁, Y₂, Y₃, B₁, B₂ and B₃+Y₄, respectively. As previously mentioned, the sheet of FIG. 2 is assumed to be printed in two colors, such as yellow and blue, requiring two "passes" through the press, first for the blue and secondly for the yellow; or, alternatively, two successive passes through separate presses which respectively print the desired colors such as yellow and blue. In the coding arrangement illustrated in FIG. 2, the code lines Y₁, Y₂, and Y₃ are yellow, the code lines B₁ and B₂ are blue, while the code line B₃+Y₄ is a superposition of yellow on blue as a test for proper color registration of the two colors. The solid area 18' is also blue. While it has been assumed for purposes of this discussion and to illustrate the coding arrangement of the invention that a separate pass is required for each color, it is also possible on a multicolor press to print more than one color in a single pass, but this possibility will not be considered in the present discussion.

There is provided on the surface of the sheet S diagonally opposite the solid area or reset bar 18', a second printed reset bar 18" to provide a stopping reset in the event the sheet S were turned. Printed area 18" is of at least the same length as printed area 18' and is positioned so as to be in the same scanning path as printed area or reset bar 18" in the event the sheet were turned. Printed area 18" might be inherent due to plate layout on the printing form, whereby the equivalent of 18" is present. If not, a separate plate could be mounted to provide for 18". The printed bar 18" does not ordinarily have any

code lines associated with it and hence does not provide a count which is fed into the counter.

There are shown in FIG. 3 the code bars used in a method of coding on printed sheets to designate the printing press "passes" and "changes" whereby a combination such as the code 16 of FIG. 2 designates a particular combination of printing press passes and changes to which the particular sheet has been subjected. In a printing press pass, as set forth in the example of FIG. 3, a sheet is passed through a printing press to have a given color printed thereon. The term "change" is defined as the use of a different printing plate or form which is placed on the press for imprinting a particular group of sheets with different printed material thereon after the completion of a run of a previous printing plate, or to the sheets which are printed thereby, the previous printing plate also constituting a "change." Thus, the particular sheet illustrated in FIG. 2 having cartons A, B, C printed thereon is a "change" (such as "Change 1") as compared to a different sheet having different printed material thereon such as, for example, cartons D, E, F, which might be "Change 2." Since the sheet of FIG. 2 is assumed to be printed in two colors, the printing of these two colors requires two "passes" through a color press, or two passes through two different color presses.

The codes lines 16 and the solid area 18' of FIG. 2 are printed by means of sheet code bars corresponding to each respective printing press "pass" which are secured to the printing forms on the press at points so located that the code lines 16 and the solid area 18' will be printed on a portion of the scrap area of the sheet which is being printed. A sheet code bar for a given "pass" remains in place for a plurality of successive "changes." A code bar is provided for each pass which each particular sheet is to make through the press. Thus, if the sheet is to make a yellow pass and a blue pass through the press, a code bar will be provided for each of these colors or passes and each of these code bars will be fastened at an appropriate place on the corresponding printing form during the corresponding pass so that the corresponding imprint will be made on the sheet of the coding for each printing press pass. This is illustrated in FIG. 3 in which there is generally indicated a master code bar 15 including nineteen code lines 16' and a solid reset bar 18'. From this master code bar a plurality of electrotype copies (for letterpress printing) or the equivalent are made, and when it is desired to produce a code bar for a particular pass, portions of the electrotype or equivalent copies are "routed out" to prepare code bars to be furnished to the pressman for each printing press pass.

Thus, as seen in FIG. 3, the code bar provided for the first pass or "blue" pass comprises three code lines B₁, B₂ and B₃, followed by the solid 18' for triggering the reset. The code bar furnished for the second or yellow pass comprises three typically two point code lines indicated at Y₁, Y₂ and Y₃, spaced typically three points apart, followed by a fourth line Y₄ in this instance spaced thirteen points apart from line Y₃. When the sheets corresponding to change 1 are run through the first or blue pass, the code lines B₁, B₂ and B₃ cause corresponding blue imprints on the sheet.

After the completion of the running of change 1 on the first or "blue" pass, the pressman changes printing plates as called for and then routes off the code line B₁, leaving only the code lines B₂ and B₃. Similarly, after the completion of the running of change 2 on the first pass, the pressman makes further plate changes and then routes off the code line B₂, leaving only the code line B₃. All of the sheets of pass 1 have the reset bar 18' printed thereon in blue. When the second or yellow pass is ready to be run, the code bar having the lines Y₁, Y₂, Y₃ and Y₄ thereon is used for the first change and these code lines are so located that lines Y₁, Y₂, Y₃ and Y₄ thereon is used for the first change and these code lines are so located that lines Y₁, Y₂ and Y₃ print to the left of the lines B₁, B₂

and B_3 , while the yellow line Y_4 prints in superposed relation to the line B_3 as a check for proper color registration.

When the sheets corresponding to change 1 are run past the electronic inspection device, if the change 1 sheets are properly coded with both the yellow and blue passes, the detection device will count six spaces; when the change 2 sheets pass by the electronic inspection device, the counting device will count four spaces; and when the change 3 sheets are moved past the inspection device, the counting device will count two spaces. In the case of counting the codes for each of the changes 1, 2, and 3, the dark area 18' is of sufficient length and density to actuate the time trigger of the counting device by providing a sufficient time interval of unreflecting or dark space to uncock the time trigger of the counter as explained earlier in the specification, to result in a resetting of the counter whether or not a proper count has been made, or to additionally actuate an alarm relay or rejecting device or the like if an improper count has been made. Thus, the dark area 18' is an important feature of the invention since without it no reset would occur on such stream fed sheets and there would be no actuation of the time trigger of the counter which is necessary in order to provide either a reset of the counter or an actuation of an alarm relay.

While the electronic inspection just described is a final inspection made after the completion of all of the printing passes, it is also within the scope of this invention to make the inspection after the completion of each printing press pass. Thus, for example, sheets which have been through only the blue pass may be inspected prior to the passage of the sheets through the yellow pass. The sheets may be inspected on any subsequent "sheet pass" following the application of previously printed matter to the sheet. A "sheet pass" is defined as the introduction of the sheet into a printing press, cutting press, varnishing machine, waxer, etc., where the opportunity is presented to inspect previously printed matter while in sheet form.

There is shown in FIG. 4 a mechanical arrangement for obtaining a reset which may be used instead of the solid printed on the sheet as previously described. In this mechanical arrangement, the press cylinder 20, which may be a die cutting press cylinder in the case of sheets, is provided with a cam 22 which closes switch No. 1 in the reset circuit of the counter at a fixed point in the rotation of the cylinder 20. The sheets 24 are fed from right to left in the view of FIG. 4 from the feeder at the right on to moving tapes on the feed board 28 which carries the sheets under the electronic scanner 26 and on into the grippers 30 which grab the sheet and feed it to the cylinder 20. The sheet on feed board 28 moves in timed relation to the rotation of press cylinder 20, so that switch No. 1 in the reset circuit is closed by cam 22 when sheet 24A, the particular sheet passing the electronic scanner 26, is at a point such that all of the code lines "A" have been read by scanner 26 and the reset zone "B" of the sheet is adjacent the scanner. Switch No. 2 is also positioned in the reset circuit in series with switch No. 1 and senses the presence of a sheet. If there is no sheet present, switch No. 2 would be open, in which case the reset circuit would not be closed when the cam actuates switch No. 1, thereby preventing false stoppage, or false sounding of an alarm.

In the operation of the mechanical reset of FIG. 4, a reset of the counter occurs for the next sheet by action of the closure of switch No. 1 by cam 22, assuming switch No. 2 is also closed by the presence of a sheet. If an incorrect count has been read into the counter when switch No. 1 is closed by the cam 22, the press cylinder 20 will stop and a light or other signal will signal the pressman that the stoppage was caused by the electronic inspection. Switch No. 2 which senses the presence of the sheet in the inspection zone may be any suitable type of switch which will accomplish this purpose, including a

photoelectric means for detecting the presence of the sheet.

The sheet inspection method of FIGS. 1-4 has numerous advantages, including the following:

5 (1) Sheets turned in the feeder pile are caught and saved.

(2) It prevents having "changes" mixed on the same sheet, for example, a mix-up such as having change 1 of pass 1 on the same sheet with change 2 of pass 2. It also catches a mixed change sheet as when a change 2 sheet is mixed in a change 3 run.

(3) It detects a sheet which has been turned after an early printing pass or has missed a pass.

15 (4) Sheets out of register between colors may be detected. The method of printing one color over another for color register check is an improvement over the color-to-color register method described in my Patent Number 3,199,450 where two lines of each color were needed.

(5) The relatively slow speed of inspection used on sheet inspection as compared to inspection of individual cartons makes a much wider color detection possible. Some tints and yellows can be read on sheet inspection which cannot be read on high speed gluer inspection.

20 (6) Glue lap code lines such as those shown at 16 in my prior United States Patent No. 3,035,380 present code plate mounting difficulties. This problem is alleviated to some extent by coding certain information such as accompanying background changes on the sheet code bars, rather than on the glue lap code bars.

25 (7) It eliminates the need for coding in extra colors for more complete zones 1 and 2 inspections under applicant's prior United States Patent No. 3,035,380 for a presence of color check, as all colors are checked on the accepted sheet during the cutting operation.

30 (8) It permits inspection of sheets that do not lend themselves to subsequent inspections, such as advertising displays, etc., that are packed for distribution directly off the press.

35 (9) Subsequent stoppages in zones 1 and 2 inspections are greatly reduced.

While there have been shown and described particular embodiments of the invention, it will be obvious to those skilled in the art that various changes and modifications may be made therein without departing from the invention and, therefore, it is aimed to cover all such changes and modifications as fall within the true spirit and scope of the invention.

What I claim as my invention is:

1. The method of marking and inspecting sheets which comprises placing a predetermined number of spaced lines on the sheet with each pass of the sheet through a printing press, electronically inspecting by reflected light said spaced lines on a subsequent pass of the sheet, transmitting signals representative of the electronic inspection to a counting device, and resetting the counting device for a subsequent sheet after the completion of the inspection of each respective sheet.

2. The method of marking and inspecting sheets as in claim 1, whereby if a sheet is mistakenly turned 180° and electronically inspected by reflected light, the resulting count will differ from the predetermined number which would be read if the sheet were properly inserted.

3. The method of marking and inspecting sheets as in claim 1 where the number of lines used for each color is at least equal to the number of stoppages made for plate changes on the form during the press run and where at least one line is removed with each change.

4. The method of marking and inspecting sheets as in claim 1 where a line in one color prints directly over a line previously printed so that, if properly registered, one count will result from the two superimposed lines.

5. The method of marking and inspecting sheets as in claim 1 where the press is sheet fed and the reset is actuated by the prolonged absence of reflected light after the passage of the sheet.

6. The method of marking and inspecting sheets as in claim 1 where the press is stream fed and the reset is actuated after the code lines are read by a light absorbing solid printed on an earlier pass and of sufficient length to actuate the reset because of the prolonged absence of reflected light.

7. The method of marking and inspecting sheets as in claim 1 where the reset is actuated by a timed switch closing after the code lines are read.

8. The method of marking and inspecting sheets as defined in claim 1 in which the sheets are fed singly in non-overlapped relation to each other.

9. The method of marking and inspecting sheets as defined in claim 1 in which the sheets are stream fed in overlapped relation to each other.

10. In a system for inspecting sheets having coding thereon, a detection device responsive to said coding, a counting device, means connecting said detection device to said counting device, means for advancing sheets past said detection device, a member movable in timed relation to the advancing sheets, a reset circuit for resetting the counting device after the passage of each sheet past said detection device, and means actuated by said member for actuating said reset circuit in timed relation to the movement of each sheet member past said detection device.

5 11. A system as defined in claim 10 in which said detection device is a photoelectric detection device.
